(57) CLAIM

The ornamental design for a racing helmet hitch ball cover, as shown and described.

DESCRIPTION

FIG. 1 is a perspective view of the racing helmet hitch ball cover showing my new design.

FIG. 2 is a front elevation view thereof;

FIG. 3 is a back elevation view thereof;

FIG. 4 is a right elevation view thereof;

FIG. 5 is left elevation view thereof;

FIG. 6 is a top plan view thereof; and,

FIG. 7 is bottom plan view thereof.

The broken lines shown on the drawings are for illustrative purposes only and form no part of the claimed design.
